UNITED STATES PATENT OFFICE.

ERICK NELSON, OF ST. PAUL, MINNESOTA, ASSIGNOR OF ONE-HALF TO
ANNA HELWIG, OF SAME PLACE.

ENGINE.

SPECIFICATION forming part of Letters Patent No. 669,245, dated March 5, 1901.

Application filed March 8, 1900. Serial No. 7,791. (No model.)

To all whom it may concern:

Be it known that I, ERICK NELSON, a citizen of the United States, residing at St. Paul, in the county of Ramsey and State of Minnesota, have invented certain new and useful Improvements in Portable Drilling-Machines, of which the following is a specification.

This invention relates to portable machines for operating drills and similar implements; and it consists in the construction, combination, and arrangement of parts, as hereinafter shown and described, and specifically pointed out of the claims.

In the drawings, Figure 1 is a side elevation with the casing in longitudinal section. Fig. 2 is a plan view, and Fig. 3 is a sectional plan view, of the device complete. Fig. 4 is a plan view, Fig. 5 is a sectional plan view, and Fig. 6 is an end elevation, of one of the operating-cylinders detached. Fig. 7 is a side view of the cylinder, with the valve-plug in section on the line $x-x$ of Fig. 6. Fig. 8 is a perspective view of the valve - bushing detached. Fig. 9 is a sectional side elevation on the line $y-y$ of Fig. 3. Fig. 10 is a sectional side elevation on the line $z-z$ of Fig. 3 with the internal gearing and connections removed. Fig. 11 is an end elevation in section on the line $w-w$ of Fig. 3. Fig. 12 is an end elevation from the "feed" end of the device.

A' is an oblong casing, preferably of cast metal and closed at one end, as at A^2 , and open at the other end, as shown.

Formed centrally through the closure A^2 is a circular opening b' , in which a bushing fits closely, the bushing being preferably in two parts b^2 b^3 , with the inner ends abutting against each other centrally of the opening b' and with annular recesses around the adjacent ends, in which a coiled spring b^4 is supported, the function of the coiled spring being to keep the two parts of the bushing pressed normally outward, as hereinafter explained. This device is intended more particularly to be driven by compressed air; but steam may be employed as the motive power, if preferred.

B' B^2 are two cylinders each having a stud B^3 and B^4 projecting centrally from one side and each stud surrounded by a sleeve B^5 and

B^6 , the outer surface of each sleeve fitting into the bushings b^2 b^3 from opposite sides and with the adjacent ends of the studs and sleeves abutting against each other, as shown 55 in Fig. 3. The outer surfaces of the sleeves B^5 B^6 and the inner surfaces of the bushings b^2 b^3 are "ground," so as to fit steam or air tight against each other.

As before mentioned, while air or steam 60 may be used as a motive power for clearness and brevity hereinafter the motive power will be referred to as "compressed air."

The studs B^3 B^4 and their sleeves B^5 B^6 and the bushings b^2 b^3 are provided with ports for 65 the passage of the air, the studs and their sleeves thus serving as the valves by which the air is admitted to the cylinders and also as trunnions or bearings on which the cylinders oscillate. 70

The manner in which the "ports" are formed in the cylinders and valves is one of the novel features of my invention and is described as follows:

The cylinders are each cast with a projecting rib d' along one side lengthwise and centrally of the studs B^3 B^4 , and the stud, rib, and cylinder are all cast in one piece, the stud and rib being solid or without the port-passages. Holes d^2 d^3 are then drilled into 80 the rib d' from either end, leaving a solid central portion d^4 between the adjacent ends of the holes d^2 d^3 , as shown. Similar holes d^5 d^6 are then bored in through the stud B^3 or B^4 , intersecting the holes d^2 d^3 , as shown. Openings d^7 d^8 are then cut into the passages d^2 d^3 , 85 near their outer ends, through the side of the cylinder B' or B^2 , to provide for the passage of the compressed air from the passages d^2 d^3 to the cylinder. The outer ends of the passages d^2 d^3 and d^5 d^6 are then fitted with plugs to close their outer ends and prevent the escape of the air. Recesses d^9 d^{10} are then cut into the plug on opposite sides and through the passages d^5 d^6 , as shown in Figs. 4, 5, 6, 95 and 7. The sleeves B^5 or B^6 , having been provided with ports d^{11} d^{12} d^{13} d^{14} , as shown in Figs. 8 and 10, are fitted over the studs B^3 or B^4 , as shown in Figs. 3 and 10, with the ports d^{11} d^{13} opposite to and leading into the recess d^9 and the ports d^{12} d^{14} opposite to and leading into the recess d^{10} , as shown in Fig. 10. 100

BUSHING

The framework or casing is formed with chambers $A^3 A^4$ on opposite sides of the inclosure A^5 for the bushings $b^2 b^3$, these chambers forming the receiving and exhaust chambers alternatively, according as the machine is running forward or backward. Ports $e' e^2$ are formed through the inclosure A^5 on opposite sides, and similar ports $e^3 e^4$ will be formed through the bushings $b^2 b^3$ and registering with the ports $e' e^2$, as shown in Fig. 10. The ports $e' e^2$ will be formed opposite each of the ports $e^3 e^4$ in the bushings $b^2 b^3$, so that the compressed air will find its way to each valve of each cylinder.

15 The outer sides of the cylinders are each provided with a trunnion D' or D^2 , located centrally of the cylinder and in line with the centers of the studs $B^2 B^3$.

20 $E' E^2$ represent two plates secured across the framework A' and covering the chambers $A^3 A^4$ and with their ends curving toward each other and provided with flanges g , by which they may be secured together, as shown. An end plate E^3 will be secured across the ends 25 of the plates $E' E^2$, as shown. Where the flanges inclose the trunnions $D' D^2$ they are formed to support the trunnions and form bearings coacting with the studs $B^2 B^3$ and their sleeves $B^5 B^6$ to support the cylinders 30 and on which the cylinders oscillate. The plates $E' E^2$ thus serve the threefold purpose of covers for the chambers $A^3 A^4$, casings to cover and protect the cylinders and their adjacent attachments, and also providing for 35 bearings to the cylinder, in which they are supported.

Within the chamber A^3 is set a perforated diaphragm A^6 to support a layer of waste or other absorbent material to receive the lubricating-oil fed in through an opening h and allowing it to percolate slowly downward to the valves and cylinders.

40 Formed in the end of the casing A' , centrally between the cylinders $B' B^2$, is a stud i' , in which a circular cavity i^2 is formed, leading inward nearly to the line of the bushings $b^2 b^3$ and forming a "seat" for the combined inlet and exhaust valve, as shown. This valve consists of a main shank F' , which also 45 forms a hand-grip by which the machine may be handled and is provided with a stud F^2 on its inner end, fitting into the cavity i^2 , and also formed with a collar i^3 , by which the shank and stud are supported in place 50 by a screw-collar or "gland" F^3 , as shown in Fig. 3. By this means the valve is supported revolvably within the framework.

55 The valve $F' F^2$ is provided with two channels $i^4 i^5$ throughout its length, one end of 60 each channel opening outward through the outer end of the shank F' and the other ends of the channels turned in opposite directions and opening outward through the sides of the stud F^2 , as shown at $i^6 i^7$.

65 $i^8 i^9$ are ports leading from the cavity i^2 into the chambers $A^3 A^4$ and registering with the outlets $i^6 i^7$ of the channels $i^4 i^5$ when the

valve $F' F^2$ is "set," as shown in Fig. 9. The channel i^4 is intended to provide means for the introduction of the compressed air, while 70 the channel i^5 is for the escape of the exhaust. The channel i^4 is shown provided with an internal screw-thread whereby the compressed-air-conducting hose may be attached. 75

By reference to Fig. 10 it will be noted that when the cylinder B' or B^2 is set "on the center" the "bridges" $d^{15} d^{16}$ between the ports $d^{11} d^{12}$ and $d^{13} d^{14}$ "cut off" the air-supply, and by increasing or decreasing the 80 widths of these bridges the "time" of the cut off may be lengthened or shortened.

The bushings $b^2 b^3$ may be so set as to provide for the requisite "lap" or "lead."

85 The piston-rods $B^7 B^8$ are connected to crank-pins $H' H^2$ on crank-heads $H^3 H^4$, which are secured on opposite ends of a transverse shaft H^5 , journaled across the framework A' , the crank-heads being set "quartering," as shown, so that the machine will not get on 90 the center. By this arrangement compressed air or steam admitted to the channel i^4 will flow into the chamber A^3 or A^4 , according as to which way the valve $F' F^2$ is turned, and from thence into the cylinder $B' B^2$ alternately through the ports $d^{11} d^{12} d^{13} d^{14}$ and 95 passages $d^2 d^3 d^5 d^6$ and recesses $d^9 d^{10}$ and be exhausted through the channel i^5 , and thus actuate the pistons and revolve the shaft H^5 .

To reverse the motion of the shaft H^5 , it is 100 only necessary to turn the valve $F' F^2$ one-half a revolution to transpose the channels $i^5 i^4$, when the air will be admitted first from the opposite side, and thus reverse the motion.

105 To shut off the supply of air, and thus stop the motion, it is only necessary to turn the valve $F' F^2$ one-fourth of a revolution to bring the ports $i^6 i^7$ of the cavity i^2 opposite the solid portions of the valve and cut off the flow of 110 the air.

To regulate the motion of the valve $F' F^2$, a collar F^4 is attached to the shank F' outside the gland F^3 and provided with two lugs $F^5 F^6$, adapted to be engaged by a stop F^7 , attached immovably to the end plate or cover E^3 of the casing, as shown.

115 The distance between the adjacent sides $m' m^2$ of the lugs $F^5 F^6$ will permit the valve $F' F^2$ to be turned one-half a revolution, so that when the collar F^4 is set, as shown in Fig. 12, the motion may be reversed or stopped entirely by turning the valve one-fourth of a revolution.

120 The distance between the adjacent sides $m' m^2$ of the lugs $F^5 F^6$ will be sufficient when the collar F^4 is reversed in position, so as to have these sides coöperate with the stop F^7 to allow the valve $F' F^2$ to be turned only one-fourth of a revolution, so that the motion will 125 be in one direction only or entirely stopped and cannot be reversed. This is an important advantage, as it is often required to run the device in one direction only, and by set-

ting the stop-ring F^4 so that the shorter space $m^3 m^4$ only is in operative relation to the stop F^7 the motion cannot be inadvertently reversed.

5 The inner end of the stud F' is formed with a cavity n' , as shown in Fig. 9, and leading from this cavity into the exhaust-channel i^5 is a vent n^2 , while other vents $n^3 n^4$ lead from a point opposite the cavity n' through the wall of the inclosure A^5 of the bushing $b^2 b^3$, and also through the bushings, to provide for the escape into the exhaust-channel of any leakage of the air around the sleeves $B^5 B^6$, which might otherwise work its way in between the adjacent ends of the sleeves and studs $B^5 B^6 B^3 B^4$ and crowd the valves and the attached cylinders outward and cause an increase of friction and leakage. By this simple expedient a "balance" is maintained 20 between the parts.

At the points where the ends of the shaft H^5 pass through the sides of the casing A' they are surrounded by and revolve in sleeves K' K^2 , the latter screw-threaded on their exteriors and tapped into corresponding screw-threads in the sides of the casing, as shown in Fig. 3. Jam-nuts $K^3 K^4$ serve to keep the screw-threaded sleeves "locked" in position in the casing. By this simple means the shaft 25 H^5 may be adjusted laterally to retain it in proper alignment with the cylinders. A pinion L' is secured rigidly to the shaft H^5 , between the adjacent ends of the screw-collars, as shown. L^2 is another transverse shaft 30 journaled by one end L^3 in the casing and fitting by a screw-thread into a sleeve L^4 , fixed in the opposite side of the casing A' , and with a nut L^5 on the end of the shaft outside the casing. The end L^3 of the shaft L^2 is larger than 35 the body of the shaft, thus providing a shoulder against which the elongated hub L^6 of an idler-gear L^7 rests, the gear thus being supported from lateral movement between the shoulder of the head L^3 and the inner face of 40 the opposite side of the casing A' , as shown.

Securely rigidly upon the extended hub L^6 is a gear L^8 , intermeshing with the pinion L' on the shaft H^5 , as shown.

M' is a sleeve screw-threaded on its exterior, as at t' , and fitting by this screw-thread into corresponding threads in the side of the casing A' and adapted to be locked in place by a jam-nut M^2 , as shown, and M^3 is another sleeve screw-threaded on its exterior and fitting by this screw-thread in the opposite side of the casing A' and adapted to be locked in place by jam-nut t^2 , as shown.

Journalized in the sleeve M^3 is a "shell" M^4 , having a tapered interior cavity and fitting 55 by its reduced inner end into the inner end of the sleeve M' , as shown, the inner end of the shell M^4 abutting against balls t^3 to reduce the friction to a minimum.

Projecting from the outer end of the sleeve 60 M' is a shank M^8 , screw-threaded on its exterior surface, preferably by square threads,

to secure additional strength, and adapted to receive an internally-screw-threaded back-center M^9 , as shown, the latter provided with handles M^{10} , by which it may be more readily 70 revolved. The shank M^8 and also the rear or inner end of the shell M^4 are hollow, as at a' , to provide for the insertion of a rod a^2 , as shown.

The shell M^4 , as before stated, has a tapered 75 interior, as shown, and is adapted to receive the butt-end of a drill or other implement which it is designed to employ in the machine. Within the tapered socket or shell another or reducing-socket M^{11} may be employed for smaller drills or other implements. The inner end of the reducing-socket M^{11} abuts against the inner end of the drifting-rod a^2 , as shown, while the outer end a^3 of the rod projects beyond the outer end of the 85 shell M^8 , so that in event of the drill becoming "jammed" in the socket the rod a^2 may be utilized to force the socket or the drill out of the shell by screwing the back-center M^9 inward against it. 90

Upon the shell M^4 is a gear M^{12} , engaging with the pinion L^7 on the shaft L^2 . By this arrangement the motion of the shaft H^5 is transmitted through the gears L' , L^8 , L^7 , and M^{12} to the socket-shell M^4 . 95

The forward part of the machine is covered and protected by a casing formed in two parts $N' N^2$, divided along a line running through the centers of the shafts $H^5 L^2$ and socket-shell M^4 , the part N^2 attached rigidly by one end to the inner edge of the transverse half-casing E^2 and conforming in outline thereto and further secured by screws N^3 to cross-bars $N^4 N^5$, connected to the sides of the casing A' , as shown. The part N' of the casing 100 is hinged at one end, as at N^6 , to the transverse half-casing E' and secured by a thumb-screw N^7 to a cross-bar N^8 on the casing A' . By this simple means the part N' may be turned back by merely loosening the thumb-screw N^7 to expose all the running parts for 105 oiling or inspection or for repairs. While every part is thus easily accessible, all the working parts are thoroughly covered and protected while in use. 110

By this simple device a drill or other implement may be operated in any location where it is possible to connect a back support for the back-center M^9 . 115

The construction is very compact, durable, 120 and simple, and every part easily and quickly accessible for repairs or inspection. All of the operative parts are adjustable and renewable, so that the "life" of the machine can be prolonged indefinitely at very small expense. All the wear of the valves of the cylinders is between the bushings $b^2 b^3$ and the sleeves $B^5 B^6$, and these parts are easily renewable at small expense when worn. The 125 interiors of the half-casings $N' N^2$ will be provided with ribs $c' c^2$, inclosing the outsides of the outer ends of the sides of the supporting- 130

framework A', as shown in Figs. 1, 3, 9, and 10, to support the half-casings and prevent lateral displacement.

Having thus described my invention, what

5 I claim as new is—

1. In a portable machine for drilling and similar purposes, a central supporting-framework, a cylindrical valve - seat extending transversely of said framework and with 10 chambers on opposite sides within said framework, partitions connecting said cylindrical valve-seat with the walls of said chambers whereby said chambers are permanently divided, two cylinders having projecting studs 15 fitting into the opposite ends of said transverse valve-seat, said studs and cylinders provided with ports for the steam or compressed air, pistons operating within said cylinders and having piston-rods connected to 20 operate the actuating mechanism, and means whereby steam or compressed air may be alternately admitted to and exhausted from said permanently-divided chambers, substantially as shown and set forth.
2. In a portable machine for drilling and similar purposes, a central supporting-framework having transverse valve-seats, two cylinders having projecting studs fitting said valve-seats, and provided with ports for the 25 steam or compressed air, pistons operating within said cylinders and having piston-rods connected to actuate the operating mechanism, closed chambers on opposite sides of said transverse valve-seats and connected thereto 30 by combined inlet and outlet ports, a circular valve-seat adjacent to said transverse valve-seat and connected by ports to said chambers, a combined inlet and exhaust valve fitting said circular valve-seat and revolubly connected therein and with extended stem, inlet- 35 passage leading through said stem and valve and registering alternately with the ports leading to said chambers, and an outlet-passage leading through said stem and valve and registering alternately with the ports leading to said chambers, substantially as shown and described.
3. In a portable machine for drilling and similar purposes, a central supporting-framework having transverse recess, a bushing for 40 said recess formed in two parts and forming a valve-seat, two cylinders having studs fitting said bushings and provided with ports for the steam or compressed air, pistons operating within said cylinders and having piston-rods connected to actuate a drive-shaft, closed 45 chambers on opposite sides of said transverse recess and its bushings, and connected thereto by combined inlet and outlet ports, and 50 springs between the adjacent ends of said bushings to keep them pressed normally outward, substantially as shown and described.
4. In a portable machine for drilling and similar purposes, a central supporting-framework 55 having transverse valve-seats, two cylinders having projecting studs fitting said valve-seats, and provided with ports for the

steam or compressed air, pistons operating within said cylinders and having piston-rods connected to actuate the operating mechanism, closed chambers on opposite sides of said transverse valve-seats and connected thereto by combined inlet and outlet ports, a circular valve-seat adjacent to said transverse valve-seat and connected by ports to said chambers, a combined inlet and exhaust valve fitting said circular valve-seat and revolubly connected therein and with extended stem, inlet-passage leading through said stem and valve and registering alternately with the ports leading to said chambers, and an outlet-passage leading through said stem and valve and registering alternately with the ports leading to said chambers, a collar upon said extended stem and having stops engaging a stop upon said framework whereby the position of the stem and valve may be controlled, substantially as shown and described.

5. In a portable machine for drilling and similar purposes, a central supporting-framework having transverse valve-seats, two cylinders having projecting studs fitting said valve seats and provided with ports for the steam or compressed air, trunnions projecting centrally from said cylinders opposite 95 said studs, pistons operating in said cylinders and having piston-rods connected to actuate the operating mechanism, chambers on opposite sides of said transverse valve-seat and connected thereto by combined inlet and outlet ports, combined covers for said chambers and inclosing and supporting casings for the cylinders and framework, said combined covers and casings curving inward at their outer ends and forming bearings for said trunnions, 100 substantially as shown and described.

6. In a portable machine for drilling and similar purposes, a central supporting-framework having transverse valve-seats, two cylinders having projecting studs fitting said 110 valve-seats, provided with ports for the steam or compressed air, pistons operating within said cylinders and having piston-rods connected to actuate the operating mechanism, closed chambers on opposite sides of said 115 transverse valve-seats and connected thereto by combined inlet and outlet ports, a circular valve-seat adjacent to said transverse valve-seat and connected by ports to said chambers, a combined inlet and exhaust valve 120 fitting said circular valve-seat and revolubly connected therein and with extended stem, inlet-passage leading through said stem and valve and registering alternately with the ports leading to said chambers, and an outlet-passage leading through said stem and valve and registering alternately with the ports leading to said chambers, the inner end of said combined inlet and outlet valve being recessed and connected by a vent to said 125 outlet-passage and also by a vent to the interior of said transverse valve-seat, substantially as shown and described.

7. In a portable machine for drilling and

similar purposes, a central supporting-framework having transverse valve-seats, two cylinders having projecting studs fitting said valve-seats, provided with ports for the steam or compressed air, trunnions projecting centrally from said cylinders opposite said studs, pistons operating in said cylinders and having piston-rods connected to actuate the operating mechanism, cover-casings for said cylinders and the said framework opposite said cylinders, a rear casing secured by its edges to said cylinder-cover casing-sections, a lower casing-section secured by one edge to one of said cylinder-cover casing-sections and ex-

tending to inclose the lower part of said framework and its connections, and an upper casing-section hinged to the other one of said cylinder-cover casing-sections, whereby access may be had to the operating mechanism, substantially as shown and described. 15

20 In testimony whereof I have hereunto set my hand in the presence of two subscribing witnesses.

ERICK NELSON.
